HUNTER'S KIT

Anthony J. Heider, Oceanside, N. Y.

Application January 7, 1947, Serial No. 720,568

4 Claims. (Cl. 224—2)

1

This invention relates to a hunter's kit or mat and has particular relation to a device of this type which is adapted to serve as a mat on which the body of the user can rest and also for carrying the gun, ammunition and other articles needed by the user.

It is one object of the present invention to provide a device of the above mentioned type which can be easily and quickly put in use when needed and easily and quickly folded and conveniently carried after use.

Another object of the invention is to provide a hunter's kit and mat which is provided with means for carrying guns and ammunition and forms a protective and comfortable support for the body of the user.

It is also an object of this invention to provide a device of the beforementioned type which can be easily and inexpensively manufactured, and is sturdy and resistant to wear and tear in use.

Other objects and the advantages of the invention will be apparent from the following specification and claims and the appended drawings which show by way of example a preferred embodiment of the invention, and in which

Figure 1 is the top view of a device according to the invention in unfolded condition, with parts broken away;

Figure 2 is a perspective view of the device shown in Figure 1, in folded condition, and with a gun held by the folded mat;

Figure 3 is a sectional view along line 3—3 of Figure 1;

Figure 4 is a sectional view along line 4—4 of Figure 1;

Figure 5 is a top view of the device in partially folded condition, and

Figure 6 is a sectional view along line 6—6 of Figure 1.

Referring now to the drawings in detail, 1 denotes a substantially oblong-shaped mat consisting of a suitable sheet material, preferably an impregnated water-impermeable textile material which is sufficiently thick for providing protection from cold owing to its heat-insulating properties. This mat 1 has two shorter edges 2 and 2', and two longer edges 3 and 3'.

One part of the inner surface of mat 1 is cushioned as shown in Figures 1 and 3, by ap-

plying and fastening a suitable textile fabric 21 and suitable stuffing material 22 to the mat 1 by means of a series of seams 23.

At its end adjacent edge 2, the mat 1 is provided with a series of aligned pockets 4, which are formed by fastening a long rectangle-shaped piece of sheet material 5, for example by stitches 6, to mat 1, and dividing the longitudinal pocket thus formed into shorter individual pockets 4, 4, by means of transverse seams 7. These pockets are adapted to hold ammunition. As best shown in Figure 3, the sheet material 5 forming the pockets 4 is reinforced at its inner longitudinal edge by an inwardly folded integral strip 8 of said material 5, fastened to 5 by seam 9. Pockets 4 are provided with flaps 10, which are cut from a single strip of sheet material fastened by stitches 11 to mat 1. Sheet material 5 and pockets 4, respectively, are provided with fastening means 12 for releasably fastening the flaps 10 and thus closing pockets 4. The flaps 10 are bordered with reinforcing strip 13.

Between the ammunition pockets 4 and its cushioned portion, the mat 1 is provided with two pockets 14 and 15, these each extending transversely outward from a side edge of the mat, pocket 14 extending from side 3 and pocket 15 from side 3'; each pocket has its inner end permanently open, a zonal portion of the material at the open end being secured to edges 3 and 3', respectively, of the mat 1 in transversely aligned position. These pockets 14 and 15 are adapted to receive a gun, pocket 14 being adapted to receive the butt, and pocket 15, the end of the barrel of the gun, as indicated in broken lines in Figure 1. As shown in Figures 1 and 6, pocket 14 is formed by an oblong-shaped folded piece 16 of a suitable textile material, which is fastened to mat 1 by seams 16', 16'', and the side edges of 40 which are fastened to each other by seams 17. The other closed end of pocket 14 is reinforced by a lining 18, consisting of a suitable material fastened by seams 18', 18''. Pocket 15 is formed by a folded rectangular piece of a suitable textile material which is fastened by a seam to mat 1. The outer end of this pocket is closed by a seam along edge 15', while two cooperating longitudinal edges are provided with and may be closed and opened by means of a zipper 19.

In the space between pockets 14 and 15, a fur-

ther pocket 20 is formed by a portion of mat 1 and an oblong-shaped piece 24 of textile material, this piece 24 being fastened to mat 1 by means of seams 24'. This pocket is adapted to hold a short gun and is provided with a fastening means 25. Pocket 20 extends to the vicinity of the open end of pocket 15, said end of pocket 20 being stitched to the mat, the opposite end of the pocket being unstitched, the fastening means 25 serving to close such end after any content has been inserted. Since the wall of the pocket is of textile material, it lies practically flat when no content is present.

Pocket 20 lies between the open end of pockets 14 and 15 and hence unoccupied pocket 23 will underlie the gun which may be positioned in pockets 14 and 15. Normally, pocket 20 will be unoccupied when a gun is being carried, but is available for a small arm when the gun is absent. However, both gun and small arm may be carried concurrently if the latter is positioned with its butt end toward the closed end of the pocket where it would be out of the path of the gun barrel, the gun being positioned in overlying relation to the top of the pocket, the textile material permitting the top wall of the pocket to accommodate the conditions set up.

While pockets 14 and 15 each extend outward from a side of the mat, and each has an open inner end within the mat zone, the two pockets differ in that pocket 15 is additionally equipped with the zipper 19 which extends in the direction of length of the pocket, and thus permits the top of the pocket to be opened. This difference in pocket formation is to make possible the positioning of the gun, the butt end of which is slipped into pocket 14, with the intermediate portion overlying pocket 20. By then creating the flap characteristic to the top of pocket 15 by opening the zipper, the end zone of the barrel is slid laterally into the opened pocket, after which the zipper is closed, thus securely mounting the gun within the assembly. While this leaves the intermediate portion of the gun uncovered, this gun portion is actually protected when the assembly is rolled up, since the open ends of the pocket are within the side limits of the mat so that when the mat is placed in the rolled-up condition, it overlies such intermediate portion of the gun.

Mat 1 is folded outward along its edge 2', forming a strip 26, which is fastened to mat 1 by seams 26' and is provided with fastening means 27, which are secured to opposite corners of mat 1, as shown in Figure 1, and are adapted to cooperate with fastening means arranged along edges 3 and 3', respectively, of mat 1. Handles 28 are secured to the end of the mat at edge 2', as shown in Figures 1, 4 and 5.

The longitudinal edges 3, 3' of mat 1 are also folded outward, and the folded strips 29 and 30 are fastened to the mat 1 by means of seams 29' and 30'. These strips are also provided with several spaced fastening means 31, adapted to cooperate with fastening means 27.

When in use, the mat 1 is spread on the ground as shown in Figure 1, and the body of the user rests on the cushioned surface of the same. In order to carry the mat, it is folded as shown in Figure 2. The user's gun and, if desired, one or more blankets are enwrapped in the mat, and the fastening means 27 are fastened to one of the cooperating fastening means 31.

It will be apparent to those skilled in the art that the present invention is not limited to the

specific details described above and illustrated in the drawings. The fastening means 27 are male parts of snap fasteners of the customary type which cooperate with one of the fastening means 31 which are female parts of the snap fasteners. Other suitable fastening means may be, of course, used instead of snap fasteners. These and other modifications may be made without departing from the spirit and scope of the invention as defined in the appended claims.

What is claimed is:

1. A hunter's kit comprising a sleeping mat which is oblong in shape and which is rollable upon itself into a compact roll for carrying purposes, a pair of looped handles fastened to the outer end of said rollable mat, said handles being made of relatively flexible material to enable them to encircle the rolled mat and to meet at a point diametrically opposite the end of the mat to which they are affixed, whereby said handles may be used to carry the rolled mat, a pair of substantially aligned pockets projecting laterally outward from the sides of the opposite end of the mat, communication being provided between said laterally extending pockets, whereby they are adapted to receive and accommodate a gun inserted therein transversely of the mat as a whole, ammunition pockets formed at the end of the mat adjacent said gun pockets and a cushion provided on said mat on the opposite side of said gun pocket zone, whereby the mat may be rolled into a compact roll with its ammunition and gun pockets forming the core zone of the roll, the cushioned portion of the mat being wrapped around said ammunition pockets to protect the ammunition and the gun against jarring.

2. In a hunter's kit, wherein the kit is adapted for transportation in rolled formation and usable as a mat when unrolled, said kit comprising an elongated mat of flexible material, said mat having one end zone formed into a succession of flapped pockets arranged side by side in the direction of width of the mat for ammunition-carrying purposes, said mat having an adjacent zone carrying lateral extensions from the opposite ends of the zone, each extension being of pocket formation with an inner open end and with the open end located within the width of the mat, said extension pockets serving as enclosures respectively for the butt and barrel ends of a gun with the intermediate zone of the gun overlying the mat, said mat having the succeeding adjacent zone formed as of tufted type serviceable for resting purposes when the kit is unrolled, the opposite end zone being equipped with handles, the mat between such handled end zone and the tufted zone having length dimensions sufficient to serve as a wrapping cover for the rolled kit, whereby the rolled kit will present the rolled assembly with the ammunition zone and the gun-carrying zone presented as the core of the rolled assembly with the gun butt and barrel end zones extending outward of the mat and protected by the extension pockets and with the core zone including the intermediate zone of the gun protected by the tufted zone wrapped thereabout and with the tufted zone protected by the wrapping zone of the mat.

3. A kit as in claim 2 characterized in that the gun-carrying zone of the mat includes an elongated pocket formation located between the open ends of the extension pockets, with such elongated pocket formation open at one end and provided with releasable closure means, said elongated

gated pocket formation being adapted to underlie the intermediate zone of the gun when present and/or carry a weapon of the small arms type.

4. A kit as in claim 2 characterized in that the extension pocket for the barrel end includes a longitudinal slit on its upper face with the slit extending from the open end of the pocket to the bottom zone of the pocket, with the slit equipped with a closure of the zipper type to thereby permit the pocket walls to be opened for the positioning or removal of the gun relative to the kit.
